DRAFT APPLYING TOOL FOR PORTABLE
MOTOR-BLOWER UNITS

Grant W. Breuer, Northbrook, and Clarence W. Lanter, Bartlett, Ill., assignors to Breuer Electric Manufacturing Company, Chicago, Ill., a corporation of Illinois

Application May 21, 1948, Serial No. 28,497

8 Claims. (Cl. 299—11)

1

This invention relates to a device for cleaning theatres, auditoriums and the like, and has for an object the provision of a relatively simple inexpensive device adapted to reduce the labor, time and expense involved in performing the various cleaning operations.

To properly clean a theatre, it is necessary to remove the trash from the floor and seats, to clean plush seats with a vacuum cleaner, and to spray the floor and seats with a germicide. Heretofore, in performing these various operations, brooms and brushes were employed for sweeping trash from the floor and household-type vacuum cleaners were employed for cleaning the plush seats and for spraying the germicide. The time, effort and expense heretofore involved in removing trash from around and between the legs of theatre seats by means of brooms and brushes, and in cleaning and spraying seats by means of household-type vacuum cleaners, is well known to those engaged in managing theatres.

The present invention contemplates the provision of an operable motor-blower unit adapted to be carried by the operator by means of a shoulder strap, the unit being provided with an improved attachment for dislodging and collecting into an accumulated pile all the boxes, paper and other trash usually found around and between the legs of theatre seats at the end of a performance. Spraying and vacuum cleaner attachments are also provided for the unit, thus providing a single unit adapted to reduce the labor and expense of each of the several operations required in cleaning theatres.

It is a further object of this invention to provide an operable motor-blower unit embodying a relatively long, rigid tubing serving as an air outlet conduit, the lower end of said conduit being connected to an air outlet nozzle which is formed and adapted to be positioned to direct a high-velocity stream of air along the surface of a floor and substantially parallel thereto so as not to cause the stream of air to carry the dust and trash upwardly over the seats. The air outlet tubing, with attached nozzle, is particularly useful in cleaning theatres having rows of seats arranged upon step portions of the floor, as the nozzle end of the outlet tubing may be inserted around the legs of the seats to dislodge boxes, paper and other trash without causing the operator to bend over.

This invention embodies other novel features, details of construction and arrangement of parts which are hereinafter set forth in the specification and claims and illustrated in the accompanying drawings, wherein:

2

Fig. 1 is a perspective view illustrating the device for cleaning theatres and the manner of using same.

Fig. 2 is a sectional view taken along the line 2—2 of Fig. 1.

Fig. 3 is a sectional view taken along the line 3—3 of Fig. 2.

Fig. 4 is a front elevational view partly in section showing a nozzle and means for attaching same to the end of a rigid conduit.

Fig. 5 is a detail side elevational view illustrating the means employed for detachably connecting the nozzle to the rigid conduit.

Referring now to the drawings for a better understanding of this invention, the device for cleaning theatres is shown as comprising a portable motor-blower unit comprising an electric motor 6 and a centrifugal blower 7. The motor and blower may be of any well known construction, such as that disclosed in our co-pending patent application, Serial No. 745,356, filed May 1, 1947, in which the armature shaft acts to drive a centrifugal fan disposed within the casing 8 of the blower. The casing 8 is provided with the usual axial air inlet opening 9 and tangential air outlet opening 11. A suitable handle 12 is secured to the motor 6 and is adapted to be engaged by a strap 13 when the motor-blower unit is supported by the operator as illustrated in Fig. 1.

One end of a flexible rubber hose 14 is connected to the tangential air outlet 11 of the blower 7, and the other end of the hose is connected to the end of a rigid tubular conduit 16 which is preferably formed of metal. Detachably connected to the lower end of the rigid metal conduit 16 is provided an air outlet nozzle 17. One end of the nozzle 17 is adapted to be telescopically engaged within the end of the rigid tubular conduit 16 by means of a resilient finger 18 which is bent inwardly at 19 for engagement in a recess 21 formed in the nozzle. The resilient finger 18 is formed in the conduit 16 by means of parallel slots 22—22 and a transverse slot 23. A tubular sleeve 24 is mounted for snug telescopic movement along the lower end of the rigid metal conduit 16.

When the sleeve 24 is disposed in its lower position as illustrated in Figs. 3 and 4, it serves to hold the resilient finger 18 against outward displacement, the beaded shoulder portion 19 then serves to engage the walls of the recess 21 to prevent displacement of the nozzle 17 from the conduit. When the sleeve 24 is moved upwardly, the nozzle may be pulled outwardly from the conduit 16 as the finger 18 is free to be displaced outwardly. To prevent accidental displacement of the sleeve 24, it is provided with an

55

L-shaped recess 26 to receive the head portion 27 of a pin 28. The pin 28 is mounted in an aperture provided in the conduit 16 and is adapted to be engaged in a slot 29 formed in the inner end of the nozzle 17. The pin 28 serves to prevent rotational displacement of the nozzle 17 relative to the conduit 16.

The nozzle 17 is formed with an air passageway having a smaller cross-sectional area than the conduit 16 for the purpose of increasing the velocity of the air leaving the nozzle. The neck portion 31 of the nozzle is preferably formed circular in cross-section and intersects the outlet portion 32 which is formed to provide a passageway of gradually increasing width and gradually decreasing height to create a relatively flat stream of air for passage along the floor of a theatre. As illustrated in Fig. 3, the outlet portion 32 of the nozzle is disposed at an angle of approximately 60° from the longitudinal axis of the neck portion 31.

In using the device thus described in cleaning a theatre, the motor-blower unit is supported upon the operator by means of the shoulder strap 13, and the rigid conduit 16 is disposed at an angle of approximately 30° to 45° from a vertical plane to direct a flat stream of air along and parallel to the floor. As illustrated in Fig. 1, it will be noted that the nozzle end of the conduit 16 is adapted to be inserted between and around the legs 33 of seats 34 to dislodge and remove boxes, paper and other trash without causing the operator to bend over. As the operator moves along between rows of seats, the stream of air passing from the nozzle 17 causes the trash to be blown toward a predetermined spot from which the trash may be collected for removal in suitable containers. The device thus described is also adapted for use as a vacuum cleaner for cleaning plush seats by attaching a dirt receptacle to the tangential air outlet 11 and attaching a vacuum cleaner hose to the air inlet 9. The device is also adapted for use in spraying germicides or insecticides by attaching a suitable spraying device to the tangential air outlet 11. The construction, method of attachment and operation of vacuum cleaner attachments and spraying attachments on devices of this type is well known in the art and does not require further illustration or description.

While this invention has been shown in but one form, it is obvious to those skilled in the art that it is not so limited but is susceptible of various changes and modifications without departing from the spirit and scope of the claimed invention.

We claim as our invention:

1. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, and a sleeve mounted for telescopic movement along said conduit to engage and prevent outward displacement of the finger from the groove formed in the nozzle.

2. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin pro-

vided on said conduit to engage said nozzle against rotation relative to the conduit, and a sleeve mounted for telescopic movement along said conduit to engage and prevent outward displacement of the finger from the groove formed in the nozzle, the inner end of said nozzle being formed with a recess to receive the inner end of said pin.

3. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, a sleeve mounted for telescopic movement along said conduit to engage and prevent outward displacement of the finger from the groove formed in the nozzle, the inner end of said nozzle being formed with a recess to receive the inner end of said pin, and means on said sleeve to engage the outer end of said pin to prevent accidental displacement of said sleeve relative to said conduit.

4. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, a sleeve mounted for telescopic movement along said conduit to engage and prevent outward displacement of the finger from the groove formed in the nozzle, the inner end of said nozzle being formed with a recess to receive the inner end of said pin, and means on said sleeve to engage the outer end of said pin to prevent accidental displacement of said sleeve relative to said conduit, said means comprising an L-shaped recess formed in the sleeve.

5. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, and a sleeve mounted for telescopic movement along said conduit to engage and prevent outward displacement of the finger from the groove formed in the nozzle, the other end of said nozzle being angularly disposed with respect to said conduit and forming a restricted passageway of smaller area than the area of the conduit.

6. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, and a sleeve mounted for telescopic movement along said conduit to engage and prevent outward displacement of the finger from the groove formed in the nozzle, the other end of said nozzle having a greater width than thickness and being angularly disposed with respect to said conduit and forming a restricted passageway of smaller area than the area of the conduit.

7. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, and a sleeve mounted for telescopic movement along said conduit to engage and prevent outward displacement of the finger from the groove formed in the nozzle, the other end of said nozzle having a greater width than thickness and being angularly disposed with respect to said conduit and forming a restricted passageway of smaller area than the area of the conduit, said tubular conduit being of sufficient length to extend at an angle from a floor to the hand of a man standing erect when the nozzle is resting upon the floor.

8. In a draft applying tool for portable motor-blower units, a rigid tubular conduit, a resilient finger provided on one end of said conduit, a nozzle having one of its ends telescopically engaged within the conduit and formed with a groove to receive the end of said finger, a pin provided on said conduit to engage said nozzle against rotation relative to the conduit, a sleeve mounted for telescopic movement along said conduit to engage and prevent outward displacement of the finger from the groove formed in the nozzle, the inner end of said nozzle being formed with a recess to receive the inner end of said pin, and means on said sleeve to engage the outer end of said pin to prevent accidental displacement of

said sleeve relative to said conduit, said means comprising an L-shaped recess formed in the sleeve, the other end of said nozzle having a greater width than thickness and being angularly disposed with respect to said conduit and forming a restricted passageway of smaller area than the area of the conduit, said tubular conduit being of sufficient length to extend at an angle from a floor to the hand of a man standing erect when the nozzle is resting upon the floor.
